(57) **CLAIM**

We claim the ornamental design for a syringe, as shown and described.

DESCRIPTION

FIG. 1 is a side elevational view of a syringe according to an embodiment of the invention;

FIG. 2 is an opposite side elevational view thereof;

FIG. 3 is a front elevational view thereof;

FIG. 4 is a rear elevational view thereof;

FIG. 5 is a top plan view thereof; and,

FIG. 6 is an underside plan view thereof.

The broken lines representing portions of the syringe form no part of the claimed invention.
